UNITED STATES PATENT OFFICE.

ERICK MOE, OF ASTORIA, SOUTH DAKOTA, ASSIGNOR OF ONE-HALF TO BERTHA MOE,
OF ASTORIA, SOUTH DAKOTA

WASHING MACHINE.

Application filed January 9, 1925. Serial No. 1,430.

To all whom it may concern:

Be it known that I, ERICK MOE, a citizen of the United States, residing at Astoria, in the county of Deuel and State of South Dakota, have invented a new and useful 5 Washing Machine; of which the following is a specification.

This invention relates to washing machines, and aims to provide novel means 10 to be employed in connection with a washing machine wherein a rotating member forms a part of the construction thereof, which rotary member being provided to insure against the articles being washed, 15 bunching in the center of the machine.

A further object of the invention is to provide a device of this character which will assist in the cleaning of the articles by creating an additional suction within the 20 body portion of the machine.

A still further object of the invention is to provide a device which may be readily and easily attached to washing machines now in use, eliminating the necessity of making alterations in the construction of the 25 machine to install the device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawings:

Figure 1 is a longitudinal sectional view 40 through a washing machine supplied with a device constructed in accordance with the invention.

Figure 2 is a longitudinal sectional view through the rotating member and cylindrical device forming the invention.

Figure 3 is a sectional view taken on line 45 3-3 of Figure 2.

Figure 4 is a sectional view taken on line 4-4 of Figure 2.

Figure 5 is a bottom plan view of the 50 cylindrical member.

Referring to the drawings in detail, the reference character 5 indicates the body portion of a washing machine which has its lower wall inclined as at 6, which inclined 55 wall merges into a relatively straight wall 7.

This relatively straight wall 7 provides a support for the rotary member 8 which is mounted within the body portion 5 to operate rapidly. The device forming the essence of the invention is indicated generally by the reference character 9 and includes a cylindrical-shaped body comprising end members 10 that are held in spaced relation by means of the vertical bars 11. These bars 11 have beveled outer surfaces 12 providing a rough surface to engage the articles under treatment to assist in removing foreign matter therefrom.

As clearly shown by Figure 4 of the drawings, the alternate bars 11 are provided with lateral cut out portions 13 extending longitudinally thereof, and defining spaces to allow fluid to pass through the cylindrical member 9 creating a suction within the body portion to further increase the washing 75 action of the device.

A flange indicated at 14 extends downwardly from the disk 10 and is provided with a plurality of cut out portions 15 which cut out portions are designed to accommodate the ribs 16 of the gyrator forming a part of the usual washing machine, so that rotary movement of the member 8 will be directed to the cylindrical member 9 to cause it to revolve.

The cylindrical body portion 9 is further supported by means of the shaft 17 which is shown as extending through the disks 10, the lower end of the shaft 17 being provided with a reduced portion 18 that fits in a suitable opening in the member 8. The upper end of the shaft 17 extends above the cylindrical member where it is reduced and fitted in an opening in the bar 19 that is secured within the body portion of the washing machine by means of bolts 20, as clearly shown by Figure 1 of the drawings.

From the foregoing it will be obvious that articles supported within the washing machine will be thrown laterally by the cylindrical body portion 9 to the end that any possibility of the articles bunching at the center of the body portion will be eliminated.

It might be further stated that due to the construction of the bars 11, a roughened surface is provided for contacting with the articles under treatment to assist in the cleaning operation.

I claim:
